(57) CLAIM

The ornamental design for a scraping device for stand mixer as shown and described.

DESCRIPTION

FIG. 1 is a front, top perspective view of a scraping device for stand mixer showing my design;

FIG. 2 is a front view thereof;

FIG. 3 is a rear view thereof;

FIG. 4 is a left side view thereof;

FIG. 5 is a right view thereof;

FIG. 6 is a top view thereof; and,

FIG. 7 is a bottom view thereof.

The broken lines illustrate portions of the scraping device for stand mixer and form no part of the claimed design.
